Specification for Design.

Patented Feb. 22, 1921.

Application filed May 15, 1920. Serial No. 381,756. Term of patent 14 years.

To all whom it may concern:

Be it known that I, HENRY J. SCHAFFER, a citizen of the United States, and a resident of the city of New York, in the borough of Brooklyn and State of New York, have invented and produced a certain new, original, and ornamental Design for an Ash-Can, Garbage-Can, or like Receptacle, of which the following is a specification, reference being had to the accompanying drawings, forming part thereof.

Figure 1 is a perspective view;
Fig. 2 is a bottom plan view;
Fig. 3 is a top plan view; and
Fig. 4 is a side elevation of an ash-can, garbage-can or like receptacle, showing my new design.

I claim:

The ornamental design for an ash-can, garbage-can or like receptacle, as shown.

HENRY J. SCHAFFER.
